MAGAZINE FORMING AND LOADING
MACHINE

Joseph M. Bowen, West Quincy, Mass., assignor
to Gillette Safety Razor Company, Boston,
Mass., a corporation of Delaware

Application September 11, 1943, Serial No. 501,987

22 Claims. (Cl. 226—14)

1

This invention consists in an improved machine for forming or partially forming magazines or receptacles from sheet material and loading them with a predetermined number of articles. The invention is herein shown as embodied in an automatic machine for forming magazines for safety razor blades from sheet metal and at the same time loading the magazines with a stack of blades including one or more blanks. The invention is not limited in its scope to any specific magazine or to receptacles for razor blades but for purposes of illustration it will be described as embodied in a machine for forming and loading the safety razor magazine described in U. S. Patent No. 2,312,502, granted March 2, 1943, on an application of Nicholas Testi for Magazines. That magazine is adapted to contain a stack of narrow end-notched blades together with one blank or dummy blade. Besides acting as a blade magazine it serves also as a dispensing receptacle for blades, that is, the loaded magazine is to be purchased by the user and he may then supply his razor with a dozen or more consecutive fresh blades and finally throw away the empty magazine, purchasing a new full magazine when the supply has become exhausted. A blank or dummy blade is located in the stack so that it is delivered when only one or two fresh blades remain in the magazine, thus warning the user that he is nearing the end of his supply.

An important feature of the invention consists in provision for handling a magazine of any sort to which has been supplied a spring which is to be located beneath the blade stack and tends at all times to lift the blade stack and to hold the uppermost blade of the stack yieldingly against the top of the magazine. In order to prevent the spring from displacing the blades during the forming or the loading operations I provide automatic hold-down means which are effective to hold the spring under compression throughout that portion of the machine cycle which includes the blade-delivering and magazine forming steps.

The machine herein shown includes in its organization a main conveyor, such as a turret, upon which the partially formed magazine or container is carried to successive operating stations and a loading turret upon which the final charge of blades and blanks is assembled before it is delivered to one of the partially formed magazines. An important feature of my invention consists in a loading turret having a multiplicity of supplying stations from which different articles may be delivered as components of a complete charge. For example, as herein shown the loading turret

2

is arranged to receive first a stack of seventeen blades, then an unsharpened blank and then a stack of three blades. The final charge consists of these twenty blades with the unsharpened blank disposed at a predetermined position in the stack. At each station of the loading turret is a supplying station which includes a supply magazine from which the blades or the blanks are drawn consecutively. In this connection another important feature of the invention consists in means for temporarily lifting the blades or blanks in these magazines until a feed slide is properly positioned beneath the stack, the means being then movable to deposit the blades or blanks evenly upon the feed slide and without danger of displacement at any stage in the operation.

Another feature of the invention consists in means for centering or squaring the blades or blanks as they are advanced toward their position on the loading turret. As herein shown the blades are centered by being advanced against a gate with converging edges and the gate is displaced to inoperative position as soon as the blades have been centered. The gate is removed in this manner so that it shall not interfere with delivery of the blades to the turret.

Novel means are also provided for throwing out of operation any selected supply magazine. Other features of the invention relate to the construction of the blade-receiving stations of the loading turret. These are arranged to receive the component portions of the stack in yielding manner and to accommodate the increasing height of the stack as it is built up. For this purpose pawls are provided which engage and hold the stack by its lowermost blade as it is built up, while space for the variable remainder of the stack is provided within a recess of the receiving station.

Other features of the invention reside in the structural details of the individual fixtures upon the main turret of the machine. Each fixture includes an anvil block upon which the partially formed magazine is received and upon which it is supported for the reception of the blade stack and for the carrying out of the forming operation. Each fixture is provided with hold-down fingers which are movable periodically to engage the blade stack and its underlying spring and to compress the spring and hold the assembled parts securely upon the anvil block. Automatic mechanism is provided for retracting the hold-down fingers to permit delivery of the stack and to permit operation of the forming tools after the stack has been delivered.

Other features of the invention reside in the construction and arrangement of forming tools for closing together the sides of the magazine upon the completed blade stack and for crimping or finally shaping the inturned flanges of the magazine and for ejecting the completely filled and shaped magazine at the completion of the operation.

These and other features of the invention will be best understood and appreciated from the following description of a preferred embodiment thereof selected for purposes of illustration and shown in the accompanying drawings, in which:

Fig. 1 is a view in perspective of the entire machine;

Fig. 2 is a corresponding view in front elevation;

Fig. 3 is a view in elevation of mechanism for squaring the blades or blank delivered by the feed slide;

Fig. 4 is a view of the machine showing the turret and associated parts in longitudinal section;

Fig. 5 is a view in perspective on an enlarged scale showing a portion of an empty magazine.

Figs. 6 and 7 are views in perspective on the same scale showing a portion of the magazine in its condition in two consecutive steps in the forming and loading cycle;

Fig. 8 is a sectional plan view on the line 8—8 of Fig. 2;

Fig. 9 is a view in perspective showing a section of the main turret with one complete fixture thereon;

Fig. 10 is a view in perspective showing a blade stack in process of delivery to the loading turret;

Fig. 11 is a view in perspective showing the rear side of the loading turret and associated magazine mechanism;

Fig. 12 is a view of the magazine mechanism shown in Fig. 10 as seen with the loading turret removed;

Fig. 13 is a detail of one of the blade-carrying stations of the loading turret;

Fig. 14 is a view in perspective showing the mechanism for closing the loaded magazine, with one of the turret fixtures in position beneath it;

Fig. 15 is a view in longitudinal section through portions of the mechanism shown in Fig. 14; and

Fig. 16 is a fragmentary view in perspective showing a portion of the feed slide operating mechanism.

Before proceeding to the detailed description of the machine its principal parts and manner of operation on the magazine will be briefly outlined since with that in mind the general construction may be more readily followed.

The machine comprises a turret 40 mounted on a vertical shaft 41 to rotate in a step-by-step manner and carrying a series of eight radially disposed fixtures to which the magazine blanks are supplied one after another by hand as each of the respective fixtures arrives at the initial station in the cycle of operations. The various magazine loading and forming operations are performed as the turret presents and positions its fixtures at successive radial stations in the rotation of the turret.

The particular magazine selected to illustrate the operation of the machine and the steps performed thereon are clearly indicated in Figs. 5, 6 and 7. The magazine blank is formed of sheet brass of suitable thickness to be worked by bending dies and retain its shape when once completed. Fig. 5 illustrates the magazine blank un-

der the condition in which it is delivered by hand to one of the fixtures on the turret. It is generally channel shaped, having a flat bottom 12, side walls 13 which extend upwardly in divergent relation and inturned flanges 14 extending from one end to the other of the blank. The rear side wall merges into a longitudinally projecting finger or key 15 by which the magazine is temporarily connected to the safety razor when a blade is to be delivered thereto. From the bottom 12 of the magazine blank a pair of pins project upwardly and by these pins the stack of end-notched blades is accurately located in the magazine with their sharp cutting edges held safely out of contact with all parts of the magazine. One pin 16 only is shown in Figs. 5-7. In the finished magazine the pin 16 is of such height as to permit the uppermost blade of the stack to be pushed forward between its upper end and the inner surface of the flanges 14 which form the top of the magazine. The other pin 17, shown only in Fig. 9, is longer than pin 16, extending fully to the plane of the inner surfaces of the flanges 14 and holding all the blades of the stack positively against reverse endwise movement in the magazine.

In the bottom of the magazine is a leaf spring 18 slotted and held in place between the pins 16 and 17 and bowed so that it tends always to elevate the blade stack. The blades 20 shown herein are single-edged blades having a notch in each end for the reception of one of the pins 16 and 17 and a central slot 21 to accommodate a portion of a safety razor. As will be presently described twenty of the blades 20 are assembled in a stack by a blade turret in the machine with a warning dummy blade 22 located as number four from the bottom. When the fixture is properly located with respect to the blade turret the complete stack of blades 20 with the dummy 22 is delivered to the partially formed magazine as indicated in Fig. 6 so that the end notches of the blades receive the upstanding pins 16 and 17. As the blade stack is delivered it is followed down by a pair of hold-down fingers 23, a portion of one of these fingers 23 being shown in Fig. 6. Among the functions of the hold-down fingers is that of pressing the blade stack downwardly and flattening the underlying bowed spring 18. The hold-down fingers 23 maintain the blade stack under pressure and the spring 18 in flattened condition as the partially formed magazine is carried to the remaining turret stations in the cycle of the machine.

After the blade stack has been assembled and delivered as above explained, the partially formed and now loaded magazine blank is brought beneath a final forming station which is located 180° from the initial station of the turret and at this station the diverging sides 13 of the magazine are bent inwardly and the inturned flanges 14 are subjected to vertical pressure bringing them into parallel relation and the magazine itself into rectangular cross-section. The hold-down fingers 23 are now retracted, whereupon the spring 18 becomes effective to elevate the blade stack and hold the uppermost blade thereon in contact with the inner faces of the flanges 14. The complete magazine in the condition shown in Fig. 7 may now be removed from the machine by an operator stationed at the 315° station of the turret.

Having thus outlined the operation of the machine, its mechanical construction will now be described in detail.

It comprises a rectangular frame having side members 26 and 27 as shown in Figs. 1 and 2, cross girts 28 and 29 and a top plate or table 30. A driving motor 31 is mounted upon the rear cross girt 29 and is connected by a sprocket chain 32 to a driven sprocket wheel fast in the inner end of a short counter shaft 34 journalled in the right-hand side frame 26. The short counter shaft 34 carries a driving pulley 35 at its outer end and a pinion 33 at its inner end. The pinion 33 meshes with the large gear 36 rotatable upon the main shaft 37 of the machine which extends transversely between and is journalled in the side members 26 and 27. The large gear 36 is part of the loose member of a one-revolution clutch 38, controlled by a foot treadle 39 pivotally mounted on the outer face of the right-hand side member 26. Details of the clutch and its controlling member will not be described since they form no part of the invention but may be of any well-known or convenient construction. It will be sufficient to say that whenever the treadle 39 is depressed, whether or not it is held down, the clutch will be tripped and the main shaft 37 will make a single revolution corresponding to 45° rotation of the main turret and 90° rotation of the blade turret as will be presently described.

Main turret

The main conveyor of the machine, comprising in this case the turret 40 already mentioned, is mounted upon the upper end of a vertical shaft 41 which is journalled in the table 30 of the frame and a bracket 42 which projects inwardly from the right-hand side member 26. Just above this bearing the shaft 41 carries a large gear 43 which in turn is driven by a gear 44 loosely mounted with a larger gear 48 on a parallel vertical shaft 45, journalled at its upper end in the table of the frame and in its lower end in the bracket 46 bolted to the cross girt 28 and extending inwardly therefrom. The shaft 45 is driven from the main shaft 37 by a bevel gear set 48-59.

Fast to the shaft 45 is a disk 49 shown in Figs. 2 and 8 and having mounted in its periphery a downwardly projecting roll 50 and an upstanding roll 51. The roll 51 co-operates with a disk 52 fast on a vertical shaft 53 journalled immediately behind the shaft 45. The disk 52 is one element of a Geneva motion and has four radial tracks formed in its lower face. Accordingly, at each revolution of the vertical shaft 45, the disk 52 and the gear 48 are advanced ninety degrees. The ratio of the gear 44, which turns with the gear 48, and the gear 43 on the turret shaft 41 is two to one. Consequently, for each complete rotation of the shaft 45 the turret shaft 41 and the turret 40 carried thereby are rotated 45°.

The downward roll 51 on the disk 49 co-operates with a disk 54 keyed to a vertical shaft 55 journalled at the left-hand side of the shaft 45. The disk 54 is one element of a Geneva motion having four radial tracks in its upper face. It will be apparent, therefore, that for each complete revolution of the shaft 45 the driven shaft 55 is advanced ninety degrees. The shaft 55, therefore, turns twice as fast as the turret shaft 41.

Turret fixtures

The turret 40 carries eight fixtures arranged thereon in 45° spacing. The turret is moved 45° in each step and the cycle of the machine may be considered as beginning when one of the fixtures

occupies its initial station, facing the front of the machine as shown in Fig. 1. In this figure only four of the fixtures are shown since a showing of the full equipment would confuse the drawings. The construction of the individual fixtures is shown in Figs. 4, 9, 14 and 15 and will now be described. Each fixture has a base block 60 which is bolted to the turret 40 and which is formed integral with an upstanding anvil block 61 having a flat rectangular upper face upon which rests the bottom 12 of the magazine blank when the latter is supplied to the fixture by the operator. To each end of the base block 60 is secured a forked side piece 62 diverging at its upper ends to receive and fit against the diverging side walls 13 of the partially formed magazine blank.

Inwardly from the base block 60 is provided a bracket 63 having an outer pair of upstanding arms 64 between which is journalled an oscillatory yoke 65. The ends of the yoke are formed as trunnions and the body of the yoke is offset rearwardly from the axis of rotation of its trunnion. Secured to the back of the yoke is a block 66 and the spaced hold-down fingers 23 already referred to are formed as a part of this block extending forwardly and upwardly above the yoke 65. To the back of the block 66 is secured a gear segment 67 which is concentric with the axis of rotation of the yoke and by which it is oscillated. The right-hand trunnion of the yoke, as shown in Fig. 14, is extended outwardly and carries a short crank arm 68. In the outer end of this crank arm is mounted a roller 69, through the medium of which the yoke is rocked at one stage in the cycle of the machine.

The bracket 63 has also a rearwardly disposed pair of upstanding arms 70 in which is journalled a short horizontal shaft 71 carrying a rocker lever shaped at its forward end as a gear segment 72 meshing with the gear segment 67 and at its rear end projecting as a substantially horizontal roller-carrying arm 73. A torsion spring 74 surrounds the shaft 71 and tends at all times to rock the segment 72 upwardly and, therefore, to depress the hold-down arms 23. The rocker lever 72, 73 is oscillated in opposition to the spring 74 by a vertical plunger 75 which is mounted for vertical movement beneath the roller of the arm 73, being guided in the bracket 63 and also in a bushing provided in the hub of the turret 40. Each plunger 75 carries at its lower end a cam roll 76, running upon a stationary circular face cam 77 fast to a bushing in the turret shaft bearing. The contour of the cam 77 is such as to lift each plunger 75 as its associated fixture is moved out of the 180° station where the final bending of the magazine-forming operation has been effected. Each plunger 75 is held raised and the associated hold-down fingers also raised to inoperative position while the fixture is being moved from this station substantially to its 45° station so that the complete magazine may be removed from the fixture at the 315° station and a fresh magazine blank presented at the initial or zero station. The cam 77 is stationary and interrupted at approximately the 45° station so that each plunger 75 is permitted to drop at this point and the hold-down fingers to advance into operative position.

As each plunger 75 approaches the 90° station it moves into the range of a cam lever 78 pivotally mounted above the table 33 of the frame and having a cam roller 79 at its rear end which is operated by a barrel cam 80 fast on the upper end of the vertical shaft 45. The cam

80 is designed to elevate the plunger 75 instantaneously to permit delivery of a blade stack to the fixture while located in the 90° station and then to release the plunger 75 and permit the hold-down fingers 23 to engage the blade stack and hold it in place before the blade-receiving fixture is moved out of the 90° station. It will be seen that so long as the turret 40 is moving movement is imparted to the plungers 75 by their passage over the stationary cam 77, but at the 90° station it is necessary to move one of the plungers while the turret remains at rest and consequently the plunger is brought into operative relation with the cam lever 78. Movement of this lever is not dependent upon turret rotation since it is actuated by the constantly rotating shaft 45.

Loading turret

The mechanism for supplying blades to the fixtures of the main turret will now be described. The vertical shaft 55 is journalled to rotate and reciprocate in an elongated bearing member 84 bolted to the table of the machine as best shown in Fig. 4. Below this bearing it carries the Geneva disk 54 already described and below that is provided a fast collar 85 against the lower end of which bears a heavy compression spring 86. The lower end of the shaft 55 is embraced between the arms of a yoke 87 mounted to swing in journals 88 bolted to the rear cross girt 29 of the machine frame. At its forward end the yoke 87 has a swivel connection with a ring 89 fitting loosely upon the lower end of the shaft 55 and held in place by a nut threaded upon the lower end of the shaft.

The forward end of the yoke 87 has a downwardly extending arm 90 which carries a cam roll 91 arranged to run on the periphery of the disk cam 92 fast on the main horizontal shaft 31. The cam 92 is timed to raise the shaft 55 and the loading turret 94 four times in each revolution of the turret and the spring 86 is effective to cushion the downward movement by gravity of the shaft with the turret. In the cycle of this turret 94 as shown herein seventeen blades are delivered to each loading station at the first depression of the turret, an unsharpened blank or dummy is delivered to each station at the second depression and three blades are delivered at the third depression. The whole accumulated stack is discharged to the main turret 40 at the fourth depression of the loading turret 94.

Each of the four stations of the loading turret comprises a rectangular block 96 attached to the lower face of the loading turret 94 by screws 95 and tapering downwardly, as shown in Figs. 4 and 11. The block is forked and has two stationary end walls 97 vertically flanged to fit the blade it is to receive. Between the end walls 97 and separated from them on both sides by recesses is a vertically movable stripper block 98 which as shown in Fig. 4 is fast to the lower end of a vertical plunger 99 and normally pressed downwardly by a compression spring 100 which encircles the plunger in a chamber provided for it in the block 96. The spaces between the end of the stripper block 98 and the side walls 97 are provided to receive with clearance the hold-down fingers 23 when the blade stack is being delivered to the magazine-holding fixture at one station of the main turret. The hold-down fingers 23 operate to assist the transfer of the blade stack from its position against the under side of the stripper-block 98 into the magazine waiting beneath it.

In the block 96 are journalled short horizontal

parallel shafts 101 and 102 connected together for equal and opposite movement by a pair of meshing gear segments 103. The shaft 101 carries a downwardly extending pawl 105 and the shaft 102 carries a corresponding pawl 104. These pawls are arranged to swing inwardly and engage the sections of the blade stack as they are delivered in position beneath the stripper block 98 and pressed upwardly against it in opposition to the compression of the spring 100. An adjustable stop screw 106 bearing against the end of the block 96 determines and limits the inward swing of the two pawls. Shaft 102 carries also a second dog 107 normally extending in a substantially horizontal direction or at right angles to the pawl 104 already mentioned. When the dog 107 is swung upwardly the shafts 101 and 102 are rocked to separate the pawls 104 and 105. The dog 107 is rocked by engagement with a pivoted latch block 108 which is mounted upon the magazine mechanism. As the loading turret 94 is moved downwardly with the blade-carrying mechanism above described the dog 107 strikes a pivoted latch 108 so that pawls 104 and 105 are carried down to the bottom of the stack or stack section in separated or open position. However, the dog 107 snaps off the end of the block 108 when the turret 94 reaches its lowermost position and when this occurs the pawls are permitted to move into their blade-engaging position. The dog 105 is shouldered for engagement with a compression spring 109 which tends always to close the pawls when permitted to do so, see Fig. 10.

The pawls 104 and 105 are retracted, as above explained, at each of the three receiving stations of the loading turret by engagement of the dog 107 by the respective latches 108, etc. of the three magazines 118, 218 and 318. Independent cam operated mechanism is, however, provided for lifting the dog 107 at the fourth or delivery station of the loading turret, after the composite stack of blades has been accumulated at the earlier stations.

This mechanism comprises a bracket 81 bolted to the table 30 of the machine frame and having an overhanging arm in which is pivotally mounted a lever 82 carrying at its inner end a roll 83 movable with the lever in a path to meet the dog 107 and lift it at the proper time in the cycle of the machine. At its outer end the lever 82 is connected through a vertical link 110 to a cam lever 111 journaled on a horizontal fulcrum shaft 136 mentioned hereinafter. The cam lever 111 is rocked by a cam 138 on the cam shaft of the machine each time the turret 40 is brought to a stop, and when this occurs the pawls 104 and 105 are separated to release the accumulated stack and discharge it into the magazine blank located beneath it in the fixture of the main carrier or turret 40.

The turret 40 is provided with a series of bushed holes 24 arranged to receive consecutively a spring operated plunger 137 mounted in an upstanding bearing 138 bolted to the table 30 of the machine frame. The plunger 137 is depressed at the proper time in the cycle of the machine by a cam 57 operating through a horizontal cam lever 58, to lock the turret in position.

Magazine mechanism

The magazine mechanisms for delivering the blades to the loading turret will now be described.

Three vertical magazines of similar construction are arranged about the periphery of the loading turret 94, the magazine 118 at the front of

the turret, the magazine 218 at the left-hand side of the turret and the magazine 318 at the back of the turret. At its right-hand edge the turret 94 is unobstructed by any magazine mechanism and overlaps the main turret 40 as shown in Fig. 2.

The magazine 118 will be described in detail and it will be understood that the construction of the other two magazines are substantially identical except as to the delivery end of the feed slide. These are individually shaped to handle the particular articles which are to be delivered by the respective magazines to the loading turret. The magazine mechanism at the front of the machine includes a bracket 112 which is bolted to the table 30 of the machine frame and includes a horizontally elongated head 113 in which are formed ways for an elongated feed slide 114. The top of the guideway is partially closed by spacer plates or bars 115 and to these are adjustably secured by bolts a bracket 116 having an upright channel section 117 as best shown in Fig. 12. The magazine 118 itself is detachably held in the upright section 117 and is shaped to contain a large supply of blades, being equipped in its opposite side walls with ribs 119 adapted to receive the end notches of the blades and guide the blades in the magazine without the possibility of contact with their sharp edges. Each feed slide 114 carries an extension piece 120, best shown in Fig. 11, which is fast to the feed slide and movable in a path above the same. The extension piece 120 carries at its forward end a carrier block 121 provided with a hardened pick-off block 122. The carrier and pick-off blocks form in effect a shelf shaped to contain the component blade stack which is to be delivered by the magazine.

The magazine 118 is designed to deliver a component stack of seventeen blades to the loading turret at each reciprocation of the feed slide 114. The magazine 218 is designed to deliver a single unsharpened blank or dummy and the magazine 318 is designed to deliver three blades so that the complete stack eventually delivered by the loading turret 94 to each fixture of the main turret 40 consists of a single stack of twenty blades and one blank or warning dummy introduced after the seventeenth blade. The parts associated with the magazine 118 are marked 101 to 155 while similar parts associated with magazines 218 and 318 are marked respectively 201 to 255 and 301 to 355. The drawing may be followed more easily in some cases by referring to corresponding parts of the three different mechanisms.

The under side of the magazine 118 is covered at its lower end by a cover plate 123, best shown in Fig. 12, and the upper surface of the pick-off block 122 is arranged to slide in contact with the lower face of this cover plate. The outer end of the feed slide 114 carries a head 124 having a downwardly extending arm which is pivotally connected to the outer end of an adjustable, horizontally disposed link 125. At its inner end the link 125 is connected to the upper end of the long arm 126 of an operating lever.

The lever arm 126 is mounted on a short shaft in a bracket 127 fast to the front edge of the table 30 and swings about a horizontal axis. Its short arm 128 projects outwardly closely adjacent to the short arm of a lever 129 mounted for oscillation about the same axis and connected to the lever arm 128 by a tension spring 130. A pair of oppositely projecting lugs or studs 131 make a positive one-way connection between the arm of the lever 129 and the arm 128. As seen in Figs. 1 and 2, one lug projects toward the right

from the arm 128 and the other lug extends toward the left from the arm 129 at substantially the same distance from the common axis of the two arms. The inner end of the lever 129 is connected through an adjustable link 132 to a cam lever 133, mounted on a horizontal fulcrum shaft 136 supported in stationary brackets in front of the cam shaft 37.

The cam lever 133 is oscillated by the cam 134 in the cycle of the machine to advance the feed slide 114 at the proper time for delivering the articles contained therein to the loading turret. It will be noted that the advancing movement of the feed slide is effected yieldingly through the spring 130. If there is any obstruction to the movement of the feed slide the lever 129 merely oscillates idly while the spring 130 is stretched and released. On the other hand the feed slide is positively retracted by engagement of the lugs 131 of the connecting levers. The limit of inward movement of the feed slide is positively and adjustably determined by a stop screw 135 which is threaded through a portion of the head 124 and contacts with the outer end of the stationary feed slide bracket head 113.

The lever 226 which operates the feed slide of the magazine 218 is connected through mechanism similar to that above described to a cam lever 233 which is operated by a face cam 234 on the end of the shaft 37 instead of an edge cam like the cam 134 which operates the feed slide 114.

The feed slide 314 of the rearmost magazine 318 is operated by a lever 329 connected through an adjustable link 332 extending in from the back of the machine to a cam lever operated by the cam 334.

Means are provided for symmetrically engaging and supporting the blades or the blank to be delivered by the respective magazines and for depositing them automatically upon the shelf at the forward end of the feed slide. These means include a fork 140 which is mounted to reciprocate vertically in ways formed in the inner face of the feed slide bracket 112. The forks of this member are arranged to straddle the feed slide 114 and to engage the lowermost blade or blank in the magazine in spaced areas on both sides of the feed slide and thus to slightly lift and support the stack of blades or blanks in the magazine until the feed slide has been retracted to its outermost position. The fork 140 is then lowered and the blades deposited squarely and without danger of tipping upon the shelf provided by the carrying block 121 of the feed slide. Each fork 140 is connected at its lower end to the short horizontal lever 141 journalled upon a stud projecting inwardly from the bracket 112 and connected by a swiveled yoke 142 to the upper end of a link 143. At its lower end the link 143 is connected to a cam lever 144 pivotally mounted upon the fulcrum shaft 136. The cam lever 144 is oscillated in the proper timed relation by cam 145 on the shaft 37.

The levers 241 and 341 of the magazines 218 and 318 are connected respectively to links 243 and 343. The link 243 is connected to a cam lever 244 mounted on a stud carried by a bracket 246 which is fastened to the left-hand side frame 27. The cam lever 244 is oscillated by a cam 245 on the shaft 37. Similarly the link 343, as shown in Fig. 8, is connected to a bell crank lever 344 projecting forwardly from its fulcrum to engage a cam 345 on the shaft 37.

The fork 140 carries a stud 147 projecting from

its forward face through a slot in a cover plate 148 which plate closes the guideway of the fork. Journalled in the bracket 126 is a short shaft 149 having at its inner end an arm 150 which underlies the stud 147. At its outer end the shaft is fast to a handle 151 by which the arm 150 may be rocked and the fork 148 manually lifted whenever it is desired to throw the magazine 118 out of operation. A latch 152 holds the handle 151 in depressed position when the fork has once been raised so that the magazine may be held out of action until the operator is ready to trip the latch.

Blade centering mechanism

Upon one side of the magazine bracket 112 as shown in Fig. 13 is mounted a bracket slide 154. This is connected to the bracket by dovetailed ways and may be adjusted horizontally by a screw 155. At its inner end it carries a cross slide 156 similarly adjustable by means of a screw 157. The cross slide 156 carries a head 158 which, as best shown in Fig. 3, has parallel vertical bores for a pair of rods 159. The rods 159 are connected above the head 158 to an upper cross head 160 and below the head 158 to the lower cross head 161. The head 158 is provided with a socket midway between the rod 159 having a compression spring 162 which tends at all times to elevate the cross head structure. Its initial or uppermost position may be determined and adjusted by a stop screw 163 which is threaded into the lower cross head and bears upon a hardened abutment projecting from the lower face of the head 158. The upper cross head carries a gate having a pair of upwardly projecting posts 164 with converging inner guide faces. The upper cross head 160 carries a central upstanding post 165 which registers with an adjustable abutment bolt 166 projecting downwardly from the loading turret at each of its stations.

The cross head mechanism carried by the head 158 constitutes a centering device for aligning the blades presented by a feed slide with each other and with the receiving device of the loading turret 94. As the blades are advanced they are centered by being pressed at their ends against the converging faces of the posts 164, then as the turret 94 is moved downwardly the abutment 166 on the turret encounters the upstanding post 165 of the upper cross head and depresses this cross head against the compression of the spring 162 just ahead of the stripper or presser block 98. The posts 164 are thus carried downwardly and release the centered stack of blades. Meanwhile, the latch piece 108 has acted on the dog 107 to separate the pawls 104 and 105 so that they pass downwardly on each side of the blade stack as indicated in Fig. 11. The feed slide is, of course, rigidly supported and consequently the presser block 98 yields upwardly to accommodate the number of blades that are included in the stack on the feed slide. At the conclusion of the downward movement of the turret 94 the dog 107 snaps past the latch 108 allowing the pawls 104 and 105 to approach each other and seize and retain between them the blades on the feed slide. Now when the turret 94 is lifted the pawls 104 and 105 carry the blade stack with them being hooked under the lowermost blade and holding the stripper block 98 compressed against pressure of its spring 100. In this condition the blades are carried to the second magazine 218 at which an unsharpened blank is presented by the appropriate feeding slide and added to the stack. They

are thereafter carried on to the magazine 318 where the final three blades of the stack are similarly presented and picked up and finally the complete stack is advanced to the delivery station of the loading turret which as already explained overlaps the left-hand side of the main turret.

Magazine die-shaping mechanism

To the rear right-hand corner of the table 39 of the frame is secured an upright press frame 170 carrying in its upper portion a horizontal crank shaft 171 which at its outer end is provided with a freely rotating combined fly-wheel and driving pulley 172. This is rotated by a belt from the pulley 35 on the right-hand end of the shaft 37, the belt passing upwardly over idlers 173. A one-revolution clutch 174 is provided between the shaft 171 and the driving pulley. This is arranged to be automatically tripped by a cam 175 on the end of the shaft 37. The cam operates a cam lever 176 which is connected through an adjustable link 177, a bell-crank lever 178 and a link 179 to the latch of the clutch.

In the press frame 170 is provided a reciprocating cross head 180 operated through link 181 from a crank pin in the overhead shaft 171. The head 180 is recessed in its lower face to receive a forked forming tool 182. The sides of this tool are provided with inwardly converging faces which engage the upper side edges of the partially formed magazine and squeeze them together into substantially parallel vertical position. The forming tool is provided with transverse recesses 183 at either side to provide clearance for the hold-down fingers 23. The forming tool is recessed to provide a central rectangular passage into which the closed magazine may pass to receive a final forming operation which consists in crimping downwardly the side flanges constituting the top of the magazine.

In order to perform this crimping operation the cross head 180 and the body of the forming tool 181 are provided with a chamber in which is mounted for free movement the shank portion 184 of the crimping die 185. This die has a forked elongated portion which extends downwardly into the passage of the forming tool 182 as best shown in Fig. 15. Its lower surface is flanged so that it engages only the inturned flanges of the magazine 13. It is formed in two pieces which extend transversely some distance beyond the shank 184 which has the shape of an inverted U. When the crosshead 180 is depressed the forming tool first operates as above explained and the closed magazine is carried up into the passage thereof. The crimping die 185 has lost motion as the magazine is advanced within the chamber of the forming tool until the magazine 13 is entirely enclosed in the passage thereof. When this occurs the horizontally extended surfaces of the crimping die back up against the lower face of the cross head and a positive crimping pressure is then exerted by the die on the inturned flanges of the magazine. Fig. 15 represents the crimping die in position at the end of the crimping step.

The crimping die 185 is in turn bored to receive a knock-out bar or stripper 186 which extends upwardly into a chamber provided for it in the shank 184 of the crimping die where it is backed up by a compression spring 187. The cross head 180 is provided with a transverse slot in which rests a cross bar 188 resting at all times upon the upper face of the shank 184 of the crimping die. A lug 189 projects forwardly from the press frame 170 on each side of the cross head and

threaded into these lugs are adjustable abutment screws 190. Each abutment screw 190 stands in the path of one end of the cross bar 188 so that as the cross head 180 moves upwardly the cross bar 188 is arrested by the abutment screws 190 with the result that the crimping die and the stripper 186 are forced downwardly. The completely formed magazine with its contained stack of blades is thereupon ejected from the cavity of the forming die and returned to the anvil block 61 of the fixture from which it was formerly removed. It rests upon this block during the further rotary steps of the main turret 40 and may be picked out by the operator or removed by automatic machinery not shown.

In one side of the movable cross head 180 are provided vertical guideways for a tripping slide 192. The cross head is chambered to receive a compression spring 193 which tends always to hold the tripping slide downwardly in its lowermost position. A screw 194 threaded into an overhead ear of the slide 192 bears upon a portion of the cross head and positively determines the initial position of the said slide itself. This tripping slide is mounted vertically above the roll 69 on the arm 68 of the turret fixture standing beneath the plunger of the press. As the cross head 180 descends the stripper bar 185 engages the stack of blades between the hold-down fingers 23, holding them in position with their spring in the magazine upon the anvil block. As soon as the blades are secured in place by the end of the stripper bar 186, which now acts as a secondary hold-down, the tripping slide 192 engages the roll 69 and retracts the hold-down fingers 23. The magazine at this point of the procedure is represented in Fig. 15, although the tripping slide does not show in this particular figure. As the turret leaves its position at the press the plunger 75 is lifted by the cam 77 so that the hold-down fingers are maintained in their retracted position until after the fixture has been returned to its initial position, the loaded magazine removed and the fixture started on a new cycle of movements.

The main horizontal shaft 37 is provided at its left end with a gear 195 which rotates with the cam 234. This gear meshes through an idle pinion with another pinion 196 fast upon the inner end of a short shaft journaled in a bracket projecting from the left side frame 27 and provided at its outer end with a circular head 197. The head has sockets in its circumferential surface into any one of which a bar may be inserted for the purpose of turning the machine over by hand.

Having thus disclosed my invention and described in detail a preferred embodiment thereof, I claim as new and desire to secure by Letters Patent:

1. A magazine-forming and loading machine comprising a turret having a plurality of magazine-holding fixtures movable intermittently with the turret from station to station thereon, separate loading and forming mechanisms located at spaced stations about the turret and operating respectively to deliver blades to the magazines presented by said fixtures and to form the magazines one after another, a hold-down device for each fixture, means for retracting the hold-down devices during the movement of the turret, and separate means for retracting the hold-down device at one station while the turret is at rest.

2. A magazine-forming and loading machine

comprising a turret carrying a plurality of magazine-holding fixtures and being movable intermittently to carry the fixtures from station to station, loading and forming mechanisms located at separate stations about the circumference of said turret, a spring-operated hold-down device for each fixture, a stationary cam for moving and retaining the hold-down devices in opposition to spring pressure while the turret is moving, and cam-operated means for moving each hold-down device while the turret is at rest with a fixture at one of the loading stations.

3. A magazine-loading machine comprising a turret carrying a plurality of fixtures, each having upstanding walls for positively locating and holding a blade magazine and being movable intermittently to carry the fixtures from station to station, each fixture having a support, a rocking hold-down device mounted on said support, an operating sector for the hold-down device, and a plunger movable in the direction of its own axis for rocking the sector while the turret stands at rest.

4. A magazine-loading machine comprising a main turret carrying a plurality of magazine-holding fixtures and being movable intermittently to carry the fixtures from station to station, a loading turret rotatable about an axis parallel and adjacent to that of the main turret and having a plurality of blade-carrying devices, and means for moving said loading turret to bring successively said blade-carrying devices to each magazine-holding fixture of the main turret carrying them while said latter turret is at rest.

5. A magazine-loading machine comprising a turret carrying a plurality of fixtures for locating and presenting magazines of sheet material for forming operations, said turret being movable intermittently to carry the fixtures from station to station, means for delivering a stack of blades to a magazine in each fixture in a predetermined position of the turret, and means carrying a forming tool reciprocating in a path above the turret for bending the sheet material of the filled magazine while the magazine is presented by the turret in another position.

6. A magazine-loading machine comprising a main turret carrying a plurality of magazine-holding fixtures and being movable intermittently to carry the fixtures from station to station, a loading turret rotatable about an axis parallel to and adjacent to the main turret, opposed members mounted in the loading turret and being movable toward each other for engaging different piles of blades at opposite ends and movable away from each other for delivering the piles to the same magazine presented at different predetermined stations of the main turret, and means carrying a forming tool reciprocating in a path above the turret for closing the filled magazine.

7. A machine for filling and forming blade-magazines, comprising in combination a main turret having a series of fixtures for supporting magazine blanks having diverging sides, a loading turret rotatable in a plane above and adjacent to the main turret, cooperating members on said loading turret for engaging at opposite ends component charges each consisting of a different number of blades and supplying the charges to a magazine having sides and presented in one of said fixtures, and means carrying a forming tool reciprocating in a path perpendicular to and above the main turret for closing the sides of the magazine about the blades therein.

8. A machine for filling blade-magazines, com-

prising a loading turret having a plurality of pairs of gripping members, each pair being constructed and arranged to hold a stack of blades beneath the turret with the ends of each stack projecting into space, a carrier movable in a path adjacent to the turret, and means for transferring successive stacks of blades to the carrier including a movable device forked to engage directly the projecting ends of each blade stack.

9. A machine for filling blade-magazines, comprising a loading turret having a plurality of spaced pairs of gripping members, each pair being constructed and arranged to hold a stack of blades in position beneath the turret, a carrier movable in a path beneath the turret and having a series of fixtures each provided with a hold-down device, means for stopping the carrier in registration with a blade stack of the turret, and means operating while the turret is at rest for retracting a hold-down device preparatory to receiving a blade stack.

10. A blade loading machine having a main turret for presenting receptacles one after another in loading position, and a loading turret co-operating therewith, a series of magazines arranged about said loading turret, feed slides of different capacities cooperating with the respective magazines and movable to transfer component charges of blades of different sizes to the loading turret, and means for delivering the accumulated charges to receptacles presented by the main turret.

11. A loading machine having a main turret for presenting receptacles one after another in loading position, and a loading turret cooperative therewith and provided with a series of upwardly yielding plungers for engaging a stack of blades, movable dogs cooperating with each plunger for maintaining the stack engaged by each plunger at a predetermined level, means for pressing successive charges of blades upwardly against said plungers, and means for retracting said dogs to release the accumulated stacks for transfer to receptacles presented by the said main turret.

12. A loading machine having a main turret for presenting receptacles one after another in loading position, and a single loading turret cooperative therewith and having a series of blade-accumulating devices therein, a series of magazines cooperating with said loading turret, a feed slide movable from each magazine to transfer blades to the said accumulating devices of the loading turret, and means having opposed members for centering the stacked blades by end engagement in their movement between each magazine and the loading turret.

13. A magazine-loading and shaping machine, having in combination, a turret carrying a plurality of open fixtures for supporting partially formed magazines, each having a bowed spring therein, means for rotating the turret to present successive fixtures at different stations, means for delivering a plurality of blades to each magazine above the spring therein, a finger mounted to rock on each fixture and being movable into position for holding down the blades and spring, and a frame carrying a forming tool movable for closing the magazine in each fixture while the said finger maintains the blades and spring in hold-down position.

14. A loading and shaping machine, comprising a support for an elongated partially formed receptacle having flanged diverging side walls, means for supporting a stack of blades therein, and a closing die having diverging faces and an

intermediate passage into which the receptacle is carried after the diverging faces of the die have acted to close the side walls thereof, and means operating within the passage to crimp the flanges of the said side walls.

5 15. A loading and shaping machine, comprising a bodily movable carrier having thereon a plurality of fixtures for receiving elongated partially formed sheet metal receptacles each having diverging side walls and containing a bowed spring and a stack of blades, a hold-down device mounted on said fixture and having spaced apart fingers movable into the receptacle for compressing the blades and spring, guiding means carrying a forming tool movable in a path above the carrier, and operating mechanism for moving the tool to close the side walls of the receptacle, the said tool having a recess for receiving the fingers of the hold-down device.

10 16. A loading and shaping machine having a fixture for a partially formed receptacle having a spring and a stack of blades therein, a hold-down device comprising part of the fixture and normally compressing the spring and blades, a die movable toward the fixture to close the receptacle and having a recess affording clearance for said hold-down, a secondary hold-down device carried by said die, and means also carried by the die for retracting the hold-down device of the said fixture as the hold-down device of the die becomes effective.

15 17. A loading machine comprising a rotatable main turret having a series of fixtures for receptacles to be filled, a loading turret having a series of blade-holding devices for progressively accumulating a charge of blades, said loading turret being mounted to rotate in a path adjacent to the main turret, driving shaft carrying two separate studs, a radially slotted disk with which one stud co-operates to drive the loading turret, and a second radially slotted disk with which the other stud co-operates to drive the said main turret at one half the speed of the loading turret, the turrets being so located that a charge of 20 blades may be delivered from one to the other.

25 18. A loading machine comprising a main turret rotatable about a fixed vertical axis, a loading turret rotatable about a vertical axis with its circumference overlapping that of the main turret, a series of blade-holding devices on the main turret, a series of blade-collecting devices on the loading turret, and means for periodically lowering the loading turret to deposit accumulated charges in the holding devices of the main 30 turret.

35 19. A loading machine comprising a main turret rotatable about a vertical axis, a loading turret rotatable about another vertical axis with its circumference lapping that of the main turret, a 40 series of blade-holding devices located in the main turret in radial relation, a series of blade-collecting devices on the loading turret, said turrets being arranged at different levels for independent rotation, and means for relatively moving the turrets in a vertical direction to deliver blades from one to the other.

45 20. A magazine loading machine comprising a turret carrying a plurality of fixtures for holding sheet metal blade magazines and being movable 50 intermittently to carry the fixtures from station to station as the turret revolves, means for cumulatively delivering supplementary components of a stack of blades to the same magazine in several different stations of the turret, automatic 55 means for holding each stack in place as de-

livered and accumulated, and means for closing each magazine upon the blade stack therein at another station of the turret.

21. A magazine loading machine comprising a carrier having a plurality of holders and being movable to advance the holders from station to station, a loading turret movable in a path adjacent to and above the carrier, a series of pairs of blade end gripping devices carried by and spaced about the lower face of the turret and each pair of gripping devices being constructed and arranged to convey a stack of blades suspended beneath the turret, and means for separating said gripping devices at predetermined stations, thereby permitting the suspended blade stacks to pass downwardly and be accumulated in the holders of said carrier.

22. A loading machine having a main turret for presenting blade receptacles one after another in loading position, and a loading turret cooperating therewith, a series of magazines arranged about said loading turret, some contain-

ing blades and one containing unsharpened warning dummies, feed slides of different capacities cooperating with the respective magazines and movable to transfer component charges of blades of different sizes and a single warning dummy to the loading turret, and means for delivering the accumulated charges to successive receptacles presented by the main turret.
